UNITED STATES PATENT OFFICE.

FRANK P. SPRINGSTEAD, OF BARTLESVILLE, OKLAHOMA.

OIL BURNER.

Application filed October 7, 1927. Serial No. 224,670.

The present invention is directed to improvements in oil burners.

The primary object of the invention is to provide a device of this character so constructed that the hydro-carbon fuel will be quickly vaporized for effective operation of the burner.

Another object of the invention is to provide a burner for this purpose which is efficient in operation, consists of a minimum number of parts, and one which can be manufactured at a very small cost.

Another object of the invention is to provide a burner of this type constructed in such manner that an abundance of air will be furnished to the combustion chambers, and further to provide a burner having relatively long jets.

In the accompanying drawings:

Figure 1 is a top plan view of the burner.

Figure 2 is a sectional view on line 2—2 of Figure 1.

Figure 3 is a sectional view on line 3—3 of Figure 1.

Figure 4 is a bottom plan view of the burner.

Referring to the drawings, 1 designates the rectangular base which is provided with longitudinal troughs 2 and transverse troughs 3 which communicate with each other.

The base 1 has an opening 4 formed therein in which is located a spider 5 having bars 6 and at their inner sections is engaged the upper end of the fuel supply pipe 7.

The end walls 8 of the base have their upper ends curved and fixed thereon in any approved manner are the ends of the transversely curved bottom plate 9, and supported by said plate in spaced relation is a transversely curved top plate 10, the space between said plates constituting a vaporizing chamber 11. Upon reference to Figures 1 and 2 it will be seen that the longitudinal edges of the plates 9 and 10 are spaced from the outer side walls 12 of the longitudinal troughs 2 to provide spaces 13 into which the jets 14 formed by the longitudinal edges of said plates open. By curving the upper edges of the ends 8 and transversely curving

the plates 9 and 10 the chamber 11 will be concavo convex in cross section in order that the oil will be compelled to flow toward the jets 14. The inner walls 15 of the troughs 2 which defines the opening 4 have their upper edges spaced from the bottom plate 9 in order to permit air to pass from the openings and flow above the troughs 2 to commingle with the vaporized oil flowing from the jets 14 to carburate the same to provide a gas which is highly combustible.

Supported upon the walls 12 are baffle flanges 15 which will obviously direct the flame upwardly when the burner is in operation.

The bottom plate 9 has fixed to its under surface a coupling 16 in which is threaded the upper end of the pipe 7, there being an opening 17 in said plate to permit the fuel to flow into the chamber 11 where it is vaporized. The troughs 3 are provided with plugs 18 which can be removed to drain excess fuel therefrom.

The base is further provided with openings 19 through which air may enter to aid combustion.

To place the burner in operation oil is permitted to flow through the supply pipe into the troughs 2 and 3, after which it is ignited. The heat from the burning oil will heat the plates 10 and vaporize the oil flowing into the chamber 11 from the pipes to the jets 14, the vaporized oil being discharged from the jets into the combustion chambers A, which are defined by the troughs 2, baffle flanges 15 and ends 8.

While the drawings illustrate a preferred embodiment of the invention, it is to be understood that in adapting the means to meet specific needs and requirements the design may be varied and such other changes in the minor details of construction may be resorted to within the scope of the invention as claimed, without departing from the spirit thereof.

Having thus described the invention, I claim:

A burner of the class described comprising a base including longitudinal troughs, baffle flanges supported by the outer walls of said

troughs, a vaporizing chamber defined by top and bottom plates disposed in spaced relation and transversely curved, the longitudinal edges of the plates defining jets, 5 said baffle flanges and troughs defining combustion chambers into which the jets discharge, the bottom plate having an opening

therein, means for conducting fuel through said opening into the vaporizing chamber, and means for conducting air to the combustion chambers. 10

In testimony whereof I affix my signature.

FRANK P. SPRINGSTEAD. [L. s.]
